BRACKET FOR ADJUSTABLE WINDOW VENTILATORS

Filed March 18, 1929

UNITED STATES PATENT OFFICE

EDWARD L. NEWSOM, OF NEW YORK, N. Y.

BRACKET FOR ADJUSTABLE WINDOW VENTILATORS

Application filed March 18, 1929. Serial No. 348,088.

This invention relates to improvements in window sash brackets for window ventilators or draft deflectors.

One of the objects of my invention is to provide an adjustable window sash bracket for retaining a removable or stationary frame to control the direction of the draft of air entering a room.

More specifically my invention relates to an adjustable hinged bracket adapted to be fastened to the sides of a frame or window casting and having provision for retaining a deflector or sash in one section of the bracket including provision for varying the angular position of said movable section to control the direction of a draft of air entering a room.

To enable others skilled in the art to more fully comprehend the underlying features of my invention, reference is had to the accompanying drawing forming a part of this specification in which

Fig. 1 is a perspective view showing my invention when positioned in a window frame.

Fig. 2 is an interior side view showing one of the adjustable brackets.

Fig. 3 is a front view of the bracket, a portion of the sash being shown in broken lines.

Fig. 4 is a section taken on the line 4—4 of Fig. 2.

Fig. 5 is a view taken on the line 5—5 of Fig. 2 and showing a portion of the deflector or sash in position.

Fig. 6 is a section taken on the line 6—6 of Fig. 2 showing a portion of the deflector or sash.

Fig. 7 is an enlarged detail view showing the top adjustable sections of the bracket.

Referring now to the drawings wherein like reference characters designate corresponding parts throughout the several views, 5 designates a window sill and 6, 7 the stiles of a window frame having the usual lower sash 8, which when partially opened necessitates a draft or air regulator or shield as illustrated by Fig. 1 of the drawings.

My invention proper consists of a novel and improved bracket shown in detail by Fig. 2 comprising a stationary plate section 9 having a straight front edge 10 and a tapered rear edge 11 so that the top 12 of the section

is somewhat broader than the bottom 13. The said stationary plate section is preferably constructed of light metal and provided with a series of screw or nail openings 14 adjacent the straight edge whereby said plate section 55 may be securely fastened to the inside of the frame of the window.

The top of the stationary plate section is also provided with a rolled top edge which is bent inwardly as at 15 and then downwardly 60 as at 16. The downwardly bent portion is curved inwardly and upwardly as at 17, 18 and provided with a slot 19 for the reception of a tongue or lip 20 cut from the upper corner of a complementary, adjustable plate section 21 which is pivotally connected at 22, adjacent the bottom of the first mentioned plate section. The plate sections 9, and 21 are substantially flush with each other so that the tongue or lip 20 must be bent slightly 65 outwardly and upwardly as at 23 so as to freely ride in the slot 19. The tongue or lip 20 thus limits the inner and outward movement of the plate section 21. The plate 21 is substantially of the same size and shape 70 as the stationary plate 9 having a straight front edge 24 with segmental slots 25 so as not to interfere with the screw heads which fasten the stationary plate to the window frame. The rear edge of the movable plate 80 or section 21 is bent inwardly at right angles as at 26 and forms a wall of a window sash guide. Spaced from the said wall or angular bent edge of the movable plate or section, I provide an angle strip 27 which is preferably 85 soldered to the inside of the said movable plate or section and together with the bent edge or wall 26 constitutes a guide for a removable window sash 28. The angle strip 27 is bent upwardly as at 30 thus spacing the side edge of the removable window sash 28 90 and affording a clearance for the top of said sash from the rolled edge of the stationary section as clearly shown by Fig. 5 of the drawing. It will be of course understood that 95 it is necessary to have a left and a right bracket which constitute a pair for attaching the same to the main window frame to receive the window sash 28. Since the movable section is pivoted to the stationary section,

50 100

it will thus be seen that an adjustment or regulation may be made to vary the draft opening for the entrance of fresh air from the outside.

5 While I have shown and described my invention with some degree of particularity, it will be realized that other modifications and changes may be resorted to under special conditions. I therefore do not wish to be limited and restricted to the exact details shown 10 and described but reserve the right to make such changes and modifications as may fairly fall within the scope of the subject matter now being claimed.

15 Having shown and described my invention, what I claim as new and desire to secure by Letters Patent is:—

1. A bracket for draft shields or window ventilators comprising a stationary section having an inwardly bent top portion and a slot therein, an adjustable section pivotally connected to the bottom of the stationary section and having an inwardly bent tongue movable in the slot of the first mentioned section, and an angle strip spaced from the rear wall of the said hinged section and forming a guide therewith for a removable sash.

2. A bracket for draft shields or window ventilators comprising a stationary section adapted to be attached to a window frame, the top of said section having an inwardly bent slotted guide, an adjustable section pivotally connected to the bottom of the stationary section and having an inwardly and upwardly bent tongue movable in said slot, an angle strip fastened to the inside wall of the adjustable section in spaced relation to the rear edge thereof and constituting a guide for a removable sash, said strip having outwardly bent portions whereby the top of the removable sash is maintained in spaced relation to the inwardly bent top portion of the stationary section of said bracket.

In testimony whereof I affix my signature.

EDWARD L. NEWSOM.
